UNITED STATES PATENT OFFICE

WILLIAM SYKES, OF ROCKFORD, ILLINOIS

AUTOMATIC DOOR OPENER

Application filed November 26, 1928. Serial No. 321,822.

My invention relates to mechanical door openers for garages and the like. While it is applicable to the larger doors of commercial garages as well as small ones connected with the residences, it is particularly applicable to the latter because of its small initial cost and negligible maintenance cost. Although satisfactory devices operated by compressed air or electricity have been perfected and used to a considerable extent upon doors of commercial garages, they have been too high in initial cost and in cost of operation to become available generally to the small car owner for his private garage. In addition these are, in most cases, rather complicated devices the repair and operation of which requires skill beyond that possessed by the average car owner and involves, in connection with a single car, labor and inconvenience greater than does manual operation of the doors.

Yet the utility of a simple device for this purpose is indisputable. The motorist returning to his garage on cold winter nights would not be compelled to approach to within a short distance of the garage doors and then get out of his car, wade through snow, perhaps, then fumble with the latch, and finally, after getting the doors open, wade back to the car through the snow. Again, in rainy weather he would not be required to expose himself in opening the doors nor in going to and from them for the purpose.

Therefore, the general object of my invention is to produce a mechanical door opener for garages which may be operated by the driver of a car without leaving his seat behind the wheel.

Other objects are the provision of a door opener of simple and sturdy construction, which is easily and cheaply constructed, and which may be operated practically without cost once the initial installation is made.

Still further objects and advantages of my construction will be evident to those skilled in the art from the description and claims together with the accompanying drawings in which—

Figure 1 is an elevation of double doors to

the inside of which my invention has been applied;

Fig. 2 is a section substantially on the line 2—2 of Fig. 1 showing the latch and latch lifting mechanism;

Fig. 3 is a section on the line 3—3 of Fig. 1 showing a top view of the latch and door stop;

Fig. 4 is an elevation of the latch;

Fig. 5 is a top view of a door with the opening mechanism attached thereto showing the closed position in dotted lines;

Fig. 6 is a section on the line 6—6 of Fig. 5 showing the guide rod collar, and

Fig. 7 is a section on the line 7—7 showing the manner in which the swinging arm is attached to the guide rod collar.

Referring more particularly to the latch releasing mechanism shown in Figs. 1, 2, 3 and 4, a releasing bar 9 is attached to the inside of a door 10 by means of two bolts 11 as shown in Fig. 1. The door in this instance swings outwardly and is hinged at 40, Fig. 5. While the exact location of the bar is not important I have found it advantageous to have it near the center of the doors for reasons which will become apparent. The bar hangs loosely from the bolts 11 to permit it to swing to and from the door. A bumper plate 12 on the outside of the door is attached to the releasing bar through a rod 13 which passes through a small opening in the door. This rod is given a slight curvature corresponding to the arc upon which it moves in order that it may pass through the opening in the door without striking the sides. The length of the rod is such as to permit the bar 9 to move between a position shown in Fig. 2 and that shown in Fig. 4 as will presently be set out. The elevation of the bumper plate is such that it will correspond with the elevation of the front bumper of the automobile used. It may, on the other hand, be made sufficiently large to accommodate all makes of cars without change. An eyelet or slot 14 is placed in the lower end of the bar and is adapted to receive therein a latch or pawl 15.

The latch 15 is attached to the door near its bottom edge, directly below the releasing bar 100

and in a position to cooperate therewith as shown, by means of a bracket 16 and a pin 17. A stop 18 is provided to prevent the latch from dropping down and dragging. The latch is provided with an inclined edge 20 along which the eyelet 14 of the releasing bar is adapted to slide and a notch 19 into which it is adapted to rest in lifting the notch 21 of the latch free from a projecting ledge 22 attached to the floor of the garage by means of lag screws 23. A bracket 24 is attached to the floor in a position to stop the inward movement of the door.

It will be seen that in order to release the latch the operator of an automobile need only drive the car up to the garage door until its bumper strikes the bumper plate. The plate will be moved inward forcing the release bar away from the door. As the bar moves inward the eyelet at the lower end moves up the inclined edge of the latch and into the notch 19 simultaneously lifting the latch and releasing it from its latching ledge. The releasing bar notch 19 prevents the bar from retarding and the latch is thus held open until the operator releases it. The bumper rod is adjusted in length to limit the movement of the releasing bar eyelet to the notch of the latch provided for it. When the latch is thus released the door swinging mechanism shown best in Fig. 5 causes the doors to swing open.

The door swinging mechanism may be attached to the doors at any desired elevation but it has been found convenient to attach it near the top where it is out of the way as shown in Fig. 1. Referring now particularly to Figs. 1 and 5, a swinging arm 25 is attached to the face of each door sill 26 by means of a bracket 27 having an end 28 bent at right angles to the body portion and a bolt 29 passing therethrough. The arm as shown is made from a strip of flat metal and near its center is twisted through a right angle to present a face parallel to the door. The outer end 30 of the arm is bent at substantially right angles to the face of the bar and the face of the door and is slotted out as shown in Fig. 7 to cooperate with a guide bar collar 31. A wire loop or similar means is employed to hold the end of the swinging arm in position.

The guide bar collar 31 consists of a portion slidably mounted upon a guide bar 33 and having an annular rim 34 at each end with a central depression to receive the end of the swinging arm. The central depression is somewhat wider than the thickness of the arm permitting angular movement thereof within the depression as the door opens and closes. The guide bar 33 is a round smooth bar slidably mounted on the door through angles 35 and 36 at each end thereof. A return stop plate 38 having a depressed center is attached to the arm in a

position to cooperate with the angle 35 in a manner shown in Fig. 6 to prevent the door from being blown shut by wind while in the open position. The ends 37 of the bar are headed to prevent them from slipping from the supporting openings in the angles. Around the guide bar, and bearing between the guide bar collar 31 and the supporting angle 36, is a spiral spring 39.

The door swinging mechanism is assembled as shown in solid lines in Fig. 5 with the angle 35 near the end of the guide rod and in a position to cooperate with the return stop 38. The angle 36 is then attached to the door 10 at a point whereby the spring 39 is placed under sufficient compression to actuate the door. It will be seen that when the door is then brought to the closed position shown in dotted lines the spring will be brought under considerable compression which will be sufficient to cause the door to swing about its hinges 40 when the latch 15 is released. While Fig. 5 shows but a single door, it will be apparent from Fig. 1 the manner in which the swinging mechanism is mounted on double doors. The same parts are used in the assembly for each door.

The manner of operation of doors embodying my invention is very simple. The operator drives his automobile up to the door and forces the bumper plate inward raising the latch and releasing the doors. When the doors are thus released the door swinging assemblies, the springs of which are under compression when closed, cause the doors to swing open. In the meantime the operator has reversed his automobile far enough to permit the doors to open. As the doors reach their open position the inner angles 35 come under the return stops 38 which act to hold them open against moderate forces such as the wind.

It will be observed by those skilled in the art that the cost of constructing my improvement is very low. No expensive or hardened parts are used except the springs, most of the parts being capable of manufacture from band or strap iron. The operation of my invention is exceedingly simple requiring no fine adjustments or complicated mechanism and, therefore, results in a sturdy construction. Although I have described it as applied to garage doors and operable by means of an automobile bumper it will be evident that the invention is applicable to swinging doors applied to other structures such as barn doors, furnace doors, and the like where the latch may be operated by the feet or hands of the operator.

While I have described in detail for purposes of illustration a particular embodiment of my invention I am aware that numerous changes may be made in my construction without departing essentially from

the spirit of the invention or the scope of the appended claims.

I claim:

1. In a door opener, means for unlatching a door comprising a releasing bar attached to the inside of the door and hanging loosely therefrom, a bumper plate outside of the door attached to said bar by means of a rod passing through the door whereby horizontal movement of the bumper plate results in corresponding movement of the releasing bar, a latch lever pivotally attached to the door near the bottom edge thereof adapted to be lifted by inward movement of said releasing bar, a projecting ledge attached to the sill beneath the door adapted to cooperate with said latch in maintaining the door in a closed position, and means attached to the floor for stopping the inward movement of the door.

2. In a door opener, means for unlatching a door comprising a releasing bar slotted near one end and at the other end attached to the inside of the door through a plurality of bolts which permit movement of the bar to and from the door but do not permit substantial movement parallel thereto, a bumper plate and rod attached to said bar, said rod passing through the door, a latch supporting bracket attached to the door near the lower edge thereof in a position to cooperate with said releasing bar, a latch pivoted on said supporting bracket and resting in the slotted end of said releasing bar having an under edge tapered toward each end with two notches interposed between said tapered portions, the tapered portion and notch at the pivotal end of said latch being adapted to cooperate with the releasing bar in lifting the latch and supporting the same in an open position, a ledge attached to the door sill beneath the latch to cooperate with the tapered portion and notch at the free end of the latch in raising the latter and locking the same when the door is closed, and a bracket attached to the floor for limiting the inward movement of the door.

3. In a door opener, means for unlatching a door comprising a releasable means for normally holding the door in a closed position, a releasing bar attached to one side of the door and hanging loosely therefrom arranged to engage said releasable means, and means positioned at the opposite side of said door adapted to be acted upon by a vehicle for causing said releasing bar to release said releasable means whereby said door may be moved to an open position.

4. In a door opener, means for unlatching a door comprising a releasing bar attached to the inside of the door and hanging loosely therefrom, means outside the door for actuating said releasing bar by an automobile, a latch having a portion attached to the door and a portion attached to the floor near the door, the portions of said latch being ar-

ranged to be drawn from contact by said releasing bar to permit the door to be opened, and means for stopping the inward movement of the door.

5. In a door opener, means for unlatching a door comprising a bumper plate on said door adapted to be actuated through contact with the bumper of an automobile, a latch having a portion attached to the door and a portion attached to a stationary body near the door, said portions being arranged to engage each other in holding said door in its closed position, means for preventing the inward movement of said door when said bumper is brought into contact with said bumper plate and means actuated by said bumper plate for drawing the portions of said latch from contact to permit said door to be opened.

In witness of the foregoing I affix my signature.

WILLIAM SYKES.
